AUTOMATIC TELEPHONE SYSTEM

Edward S. Peterson, Elmwood Park, Ill., assignor
to Associated Electric Laboratories, Inc., Chi-
cago, Ill., a corporation of Delaware

Application October 19, 1934, Serial No. 749,023

22 Claims. (Cl. 179—26)

The invention relates to telephone systems in general, but is concerned more particularly with semi-automatic telephone systems whereby connections between manual lines entering an exchange may be set up by automatic switches under the control of an operator at a switchboard at a remote exchange.

The main object of the invention is the production of new and improved circuit arrangements for simplifying and improving the operation in semi-automatic magneto telephone systems of the type disclosed in application Ser. No. 676,439, filed June 19, 1933, now Patent 2,010,372, granted Aug. 6, 1935, in the name of E. S. Peterson. In the above application connections are set up between manual magneto lines by automatic switching apparatus responsive to control exercised over a control trunk extending between the manual magneto exchange and a remote operating center. This type of system was designed to improve service in rural communities by making it possible for a remote operator, instead of a local operator, to control the connection. This equipment is intended to replace manual magneto switchboards which cannot possibly carry the cost of a local operator. Remote controlled exchanges of this type are generally referred to as R. C. X.'s. In a system of this type, the local subscriber, upon initiating a call by turning his hand generator, causes a finder in the local exchange to find his line and signal the remote operator over a control trunk extending to the remote operating center or main exchange. The remote operator answers the call, dials back over the same control trunk, thereby establishing the desired connection to the local called line, and then rings the party. The remote operator then retires from the local connection and either the local calling or called parties can release the local connection by turning the hand generator.

Another object of the invention is the provision of improved dialling and control circuits in the operator's control trunk to eliminate marginal operations which may cause trouble due to differences in ground potential between the R. C. X. and the remote operating center.

Another object of the invention is the provision of means whereby common battery lines may be connected to an exchange of this type which is primarily designed for manual magneto lines.

One feature of the invention relates to the means whereby the operator is automatically disconnected from the calling line and automatically connected to the called line regardless of the idle or busy condition of the called line after the con-

trol operator has completed dialling the called subscriber's number.

Another feature relates to the repeating coil in the common equipment which enables a grounded line having its negative line conductor grounded, another grounded line having its positive line conductor grounded, and the control operator to be connected in a three way talking circuit in such a manner that the first subscriber's line will not short out the second subscriber's line.

Another feature relates to the means whereby the control operator is signalled over the control trunk when all of the links of the local R. C. X. are busy, and if the control operator should release after answering this signal without supervising, such operator is automatically resignalled.

Other objects and features of the invention will be apparent upon a further perusal of the specification in connection with the detailed description of the accompanying drawings in which Figs. 1 to 6, inclusive, show the detailed circuits.

Referring now to Fig. 1 the upper left-hand circle diagrammatically represents a plurality of well known magneto substation circuits in which the ringers thereof may be connected to either line conductor and ground or may be bridged across the line conductors. The lower left-hand circle diagrammatically represents a plurality of common battery substation circuits having their ringers connected to either line conductor and ground or bridged across the line conductors. LC shows the line circuit of one of the regular magneto lines, and LC—1 the line circuit for one of the common battery lines. Relays 51 and 52 show a so-called line adapter for enabling the common battery line to be connected to an exchange of this type. The finder switch F is of the well known rotary type in which the wipers move step by step on the deenergization of its motor magnet and in which the wipers remain in the position last used.

Fig. 2 represents the local connector permanently associated with the finder F. The local connector is of the well known Strowger type having vertical and rotary movement. The normal post spring TOLL-PS-1 operates when the connector is raised opposite the level in which the toll trunks terminate.

Fig. 3 shows the distributor for preselecting idle local finder-connector links, such as the one shown in Figs. 1 and 2. The distributor comprises a well known step-by-step rotary switch similar in construction to the finder F and an associated group of relays.

Fig. 4 shows the common equipment compris-

ing a group of relays which are common to all the local finder-connector links for controlling the operation thereof.

Fig. 4a shows a group of relays for converting the circuits shown in Fig. 4 to provide for divided ringing. When Fig. 4a is connected with Fig. 4 the dotted lines shown in Fig. 4 are cut and the relays of Fig. 4a are connected in the circuit by connecting corresponding terminals indicated by 10 circles.

Fig. 5 shows a supervisory switch for enabling the remote operator to supervise the apparatus in the R. C. X. This switch is also of the well known rotary step-by-step type. A local emergency operating center indicated by the square in the center of the drawing is somewhat similar to the remote operating center shown in the dotted rectangle in the lower left-hand corner. The equipment located at the remote operating center 15 comprises the usual operator's headset, calling device CD, repeating coil RC2, an answer key, a two-way monitor and ring key, and signalling means.

Fig. 6 shows a jack ended toll trunk terminating 25 in the remote operating center or another distant exchange. The equipment comprises the usual jack J and drop, the repeating coil RC4 and the ringing key. The toll trunks are accessible from the toll levels of the local connector banks. The 30 toll trunk also terminates in the toll line circuit shown to the right in Fig. 6.

Having given a general description of the system and drawings, the detailed circuit operations will now be explained.

35 For this purpose it will be assumed that one of the regular magneto subscribers wishes to be connected to another local station. The calling subscriber operates the hand generator at his telephone in the usual manner, projecting ringing current over his line conductor and through the upper winding of line relay 11. This ringing current passing through the upper winding of line relay 11 causes the energization of relay 11 which therefore at armature 13 connects negative battery through the winding of cut-off relay 12 to the third bank contact accessible to the finder wiper 61. At armature 14 relay 11 closes a circuit extending through the lower winding of line relay 11, armature 18, finder start conductor 50 30, and through the winding of start relay 201 to ground. Line relay 11 immediately locks itself over this circuit and start relay 201 energizes. At armature 15 line relay 11 opens a point in its original energizing circuit. Start relay 201, 55 upon energizing, at armature 212 completes an obvious circuit for energizing slow to operate relay 202 and at armature 213 completes a circuit for energizing relay 203 after the distributor has preselected an idle trunk in the connector link. 60 Relay 202 energizes after an interval and at armature 215 completes a short circuit around its winding to cause this relay to deenergize after an interval. Relay 202 therefore intermittently energizes and deenergizes and at armature 214 65 connects and disconnects ground from conductor 270 to generate a tone in the control trunk which if in use on another call will inform the control operator that another call has been initiated by another subscriber. The circuit for 70 energizing relay 203 may be traced as follows: from ground by way of conductors 262, armature 232 and resting contact, conductor 273, armature 330, conductor 281, armature 237 and working contact, armature 245, armature 213, through the 75 winding of relay 203, interrupter springs 245 of

motor magnet 253, and through the winding of motor magnet 253 to battery. In case the wipers of the distributor were resting in engagement with a busy finder-connector link then the ground on guard conductor 65 extending by way of wiper 255, and armature 221 and resting contact, short circuits relay 203 to prevent its energization. All-link-busy relay 208 is maintained in energized position as long as one of the finder connector links is idle. The circuit for maintaining all-link-busy relay 208 in energized position may be traced as follows: from grounded springs 124 of the busy keys in all of the idle local connectors thru the off normal springs 122 of the idle connectors, armature 117, by way of 15 the common chain conductor 69 and through the winding of relay 208 to battery. It should possibly be mentioned at this time that conductors 260, 261 and 262 may, if desired, extend to a relay group such as the relay group shown in Fig. 5 20 in the above mentioned application, for enabling an operator's control trunk to be switched from one R. C. X. to a second similar R. C. X.

Relay 203, upon energizing over the above traced circuit, at armature 219 maintains all-link-busy relay 208 in energized position, at armature 220 completes a circuit for energizing motor magnet 64 of the preselected idle finder-connector link, at armature 221 opens the stepping circuit to motor magnet 253 and prepares a point 30 in the circuit to relay 103 and relay 104 in the local connector, at armature 222 completes circuits for relays 217 and 205, and at armature 223 closes the test circuit through the winding of relays 206 and 207.

Relay 205 energizes by way of armature 218 before the slow to operate relay 217 is fully energized and operates its weighted armature 226 to close springs 286 and 288, thereby completing an obvious circuit for slow to release 40 relay 204. At armature 225, relay 204 completes a locking circuit for itself independent of springs 286 and at armature 216 opens a point in a circuit extending to motor magnet 253 before slow-to-operate relay 217 closes its armature 224. 45 Slow-to-operate relay 217, upon energizing, at armature 224 prepares a circuit for motor magnet 253 and at armature 218 opens the circuit of relay 205. Relay 205 releases its weighted armature 226 which now vibrates between springs 50 287 and 288 to hold the slow-to-release relays 204 in energized position for a predetermined time. This predetermined time is approximately four seconds or sufficient time to associate the calling line to an idle finder-connector link.

The circuit for energizing the motor magnet 64 of the preselected finder-connector link may be traced as follows: from ground by way of armature 220, armature 228 and resting contact, armature 221, wiper 257 in engagement with 60 the bank contact terminating the preselected link, conductor 67, and through the winding of motor magnet 64 to battery. Motor magnet 64, upon energizing, positions its pawl preparatory to stepping the wipers of the finder and at armature 63 grounds conductor 66 to complete a circuit for the stepping relay 206 in the distributor. This circuit may be traced from grounded conductor 66 by way of the distributor bank contact and wiper 256 and through the upper winding of stepping relay 206 to battery. At armature 221 relay 206, upon energizing, opens the circuit to motor magnet 64 which thereupon deenergizes. Motor magnet 64, upon deenergizing, advances the wipers of the finder one step 70 75 75

and at armature 63 opens the circuit to stepping relay 206. Stepping relay 206 deenergizes and at armature 227 recloses the circuit to motor magnet 64. This interaction between magnet 64 and stepping relay 206 continues until the test wiper 61 of the finder encounters the marked calling potential applied to the bank contact of the calling line.

When wiper 61 of the finder encounters the marked calling potential relays 206, 207 and 12 are energized in series over the following circuit: from ground by way of conductor 260, armature 223, through the lower winding of stepping relay 206, through the upper winding of test relay 207, wiper 258, conductor 68, wiper 61 in engagement with its third bank contact, conductor 24, armature 13 and through the winding of cut-off relay 12 to battery. Stepping relay 206 is maintained energized over this circuit to open the circuit to motor magnet 64, at armature 227. Cut-off relay 12, upon energizing, at armature 16 opens the original energizing circuit of line relay 11, at armature 17 connects its winding to conductor 24 independent of armature 13, and at armature 18 opens the circuit to start relay 201 and the locking circuit extending through the lower winding of line relay 11. Line relay 11, thereupon deenergizes and at armature 15 prepares a point in the talking circuit to the calling line.

Test relay 207, upon energizing, at armature 228 opens a further point in the stepping circuit to magnet 64, and completes a circuit through its working contact from grounded armature 220 for energizing motor magnet 253. At armature 230 test relay 207 grounds conductor 65 to complete an energizing circuit for relays 103 and 104 in the local connector. At armature 231 completes a locking circuit through its lower winding to grounded conductor 264, at armature 232 opens the circuit to relays 203 and at the working contact and armature 232 completes a circuit for energizing relay 430. Start relay 201 deenergizes when its circuit is opened by relay 12 and at armature 212 opens the circuit to relay 202, which now deenergizes. At armature 213 relay 201 opens a further point in the circuit to relay 203. Motor magnet 253 energizes in response to the operation of test relay 207 and positions its pawl preparatory to stepping the wipers of the distributor. At interrupter springs 254 motor magnet 253 opens a further point in the circuit of relay 203.

Relays 103 and 104 in the local connector are energized over the following circuit: from ground by way of armature 230, working contact and armature 221, wiper 255, conductor 65, springs 123 of the busy key, off normal spring 125 and resting contact, through the winding of relay 103 to battery and by way of the normally closed springs controlled by armature 140 through the winding of relay 104 to battery. At armatures 115 and 119 relay 103 prepares points in the talking circuit to the calling line, at armature 117 disconnects one of the multiple grounds from the chain conductor 69, at armature 118 completes a locking circuit for itself from grounded armature 112, armature 116 connects ground at armature 155, to the connector hold conductor 68 to hold the cut-off relay 12 in the calling line circuit in energized position. At armature 120 relay 103 opens a point in the circuit of the release magnet 109. Connector relay 104, upon energizing, at armatures 127 and 137 connects the calling line to the talking con-

ductors 268 and 269 in the common equipment, at armature 128 connects the negative ring conductor 187 to the wiper 151; at armature 136 connects the positive ring conductor 188 to wiper 154, at armature 129 connects ground to wiper 152, at armature 130 prepares a circuit for vertical magnet 111, at armature 131 prepares a circuit for the cut-through relay 105, at armature 134 prepares a circuit for rotary magnet 110, at armature 135 prepares a circuit for release relay 102, and at armature 132 prepares the circuit for relay 106.

Relay 203 deenergizes after an interval and at armature 219 removes one of the ground connections from conductor 69. At armature 220 relay 203 opens the circuit to motor magnet 253 to deenergize the same. At armature 221 closes the preselecting searching circuit to enable the distributor to preselect an idle link, at armature 222 opens the circuit of relay 217, and at armature 223 opens a point in the test circuit. Motor magnet 253, upon deenergizing, steps the distributor wipers 255 to 258, inclusive, one step and closes its interrupter springs 254 to complete the preselecting circuit by means of which the distributor preselects an idle link. In case wiper 255 is in engagement with a bank contact terminating the guard conductor of a busy link then such conductor is grounded with the result that a self interrupting circuit is completed for motor magnet 253 as follows: from grounded bank contact engaged by wiper 255, armature 221 and resting contact, interrupter springs 254, and through the winding of magnet 253 to battery. Motor magnet 253 operates in the same manner as a buzzer as long as wiper 255 engages grounded bank contacts and stops when wiper 255 no longer encounters a grounded bank contact. Since all of the busy links have their guard conductors, such as conductor 65, grounded then the motor magnet 253 will continue to step the wipers of the distributor until such time as wiper 255 stops on a bank contact terminating a non-grounded conductor 65. Relay 217 deenergizes after an interval, and at armature 218 prepares a circuit to relay 205. Relay 204 likewise deenergizes after an interval after the weighted arm 226 stops vibrating between springs 286 and 288.

At this time it may be advisable to describe the function of the slow releasing device when, due to some fault, a finder does not switch through and connect the calling line. In this case test relay 207, due to a fault, does not energize, and after a predetermined time relay 204 deenergizes and at armature 216 energizes motor magnet 253 by way of armature 224. Motor magnet 253 at interrupter springs 254 opens the circuit to relay 203 which thereupon deenergizes. At armature 222 relay 203 opens the circuit to relay 217 which deenergizes and at armature 224 opens the circuit to motor magnet 253 to cause the wipers to search for another idle finder connector link.

Relay 430 energizes in response to the operation of test relay 207 over the following circuit: from grounded conductor 262, armature 232 and working contact, armature 252, conductor 263, normally closed springs controlled by armature 431, and through the winding of relay 430 to battery. At armature 432 relay 430 opens the loop circuit extending over the control trunk conductors 351 and 452 to the remote operating center and at armature 433 completes the circuit for energizing the slow-to-operate relay 431 as

- follows: from ground by way of armature 433, conductor 291, armature 289, conductor 290, and through the winding of relay 431 to battery. At armature 434 relay 431 prepares a point in the circuit of relay 303, at armature 439 closes a circuit to the local emergency operating set, at armatures 435 and 436 disconnects the supervisory switch, at armature 438 locks itself to grounded conductor 264 by way of conductors 291 and 290, 5 at armature 437 opens the circuit to slow-to-release relay 430, and at armature 441 prepares a point in the circuit for short circuiting the right-hand winding of the repeating coil RC1 in the common equipment.
- 10 15 Relay 470 at the remote operating center is normally energized over the control trunk as follows: from ground through the lower windings of relays 302 and 301, conductor 271, lower left-hand winding of repeating coil RC1, conductor 452, lower right-hand winding of repeating coil RC2, upper low resistance winding of relay 470, through the lower high resistance winding of relay 470, resistance R, working contact and armature 312, normally closed springs 20 controlled by key springs 462, upper right-hand winding of repeating coil RC2, trunk conductor 451, armature 432, upper left-hand winding of repeating coil RC1, conductor 270, and through the upper windings of relays 301 and 302 in 25 series to battery. Due to the inclusion of the resistance R and the high resistance winding of relay 470 line relay 302 in the common equipment is not energized. In addition relay 301 being a differential relay likewise does not energize over 30 this circuit. Relay 470 in the remote operating center deenergizes when relay 430 at armature 432 opens the previously traced circuit therefor. At armature 472 relay 470 interrupts its own circuit and substitutes relay 471 which thereupon 35 energizes over the control trunk when relay 430 deenergizes, which it does an interval after relay 431 opens its circuit at armature 437. Relay 430, upon deenergizing, at armature 432 completes the circuit over the control trunk for energizing relay 471 by way of armature 472 and its resting 40 contact. At armature 475 relay 471 completes the circuit for lighting the lamp 474 to signal the operator at the remote operating center. In addition, in case the night alarm key NA is 45 closed as shown in the drawing, then the de-energization of relay 470 at armature 413 completes a circuit for operating the buzzer over an obvious circuit to sound an alarm and thereby attract the operator's attention.
- 50 55 In response to the operation of the signal 474 the control operator operates the key K to throw her head-set across the terminals of the left-hand windings of repeating coil RC2 by way of springs 460 and 464. The operation of key K also opens 60 the circuit of relay 471 at the normally closed springs controlled by springs 462 and in addition substitutes the upper low resistance winding of relay 470 for relay 471. Relay 470 is now energized from ground and battery through the windings of line relay 302 in the common equipment over the previously traced circuit through the right-hand windings of repeating coil RC2 and thence by way of the upper winding of relay 470, springs 461, impulse springs 469 of the calling device CD, spring 462 and working contact. At 65 armature 472 relay 470 opens a further point in the circuit of relay 471 and at its working contact prepares a circuit for including the resistance R and the high resistance lower winding in series 70 with the control trunk when the key K is released.

At armature 473 relay 470 opens the buzzer circuit.

In case a pay-station telephone originates a call a relay tone group (not shown) is started in operation and connects pay-station tone to conductor 270 in the same manner that the pay-station tone group PST shown in Fig. 1 in the aforesaid application by the operation of the relay group connects pay-station tone to the line conductor. In the present application the pay-station tone is connected directly to the control trunk by way of conductor 270 instead of to the pay-station line conductor.

If another local R. C. X. subscriber should initiate a call at this time, start relay 201 and relay 202 will operate in the same manner as previously described, and in this case the intermittent operation of relay 202 connects ground by way of armature 214 and the resistance to conductor 270 to notify the operator that a second call is awaiting her attention. In the present application waiting tone is put on immediately in response to the initiation of a call.

When the low resistance upper winding of relay 470 in the remote operating center is bridged across the trunk conductors 451 and 452 by the operation of key K, line relay 302 is energized thereover by way of conductors 270 and 271 over the previously traced circuit. At armature 317 relay 302 disconnects ground from conductor 271 and at armature 318 completes a circuit for energizing slow-to-release relay 305. At armature 322 relay 305 grounds conductor 278 and completes a circuit for energizing slow-to-release relay 306. At armature 323 relay 315 prepares a point in the impulsing circuit and at armature 326 maintains conductor 264 grounded. At armature 325 relay 306 prepares a point in the cut-through and release circuits, at armature 327 grounds the tone start conductor and the lock conductor 390, at armature 328 grounds the ringing machine start conductor and removes one of the grounds from conductor 264, and at armature 330 opens a point in the original energizing circuit of relay 203.

All of the foregoing operations have occurred as the result of a subscriber initiating a call, and in response to the control operator operating her dial and answer key K. The operator now answers the call and receives the number of the line to be called. The talking circuit between the calling subscriber and the control operator may be traced as follows: from the calling line over line conductors 22 and 23, wipers 60 and 62, conductors 72 and 73, armatures 115 and 110, armatures 143 and 147 and their resting contacts, armatures 127 and 137, conductors 185 and 186, resting contacts and armatures 329 and 331, conductors 268 and 269, repeating coil RC-1, conductors 451 and 452, repeating coil RC-2, key springs 460 and 464, to the operator's telephone circuit. After receiving the number of the desired called subscriber the operator will operate the calling device CD in accordance with the first digit of the called number. Since springs 465 to 468, inclusive, operate and close on the first movement of the calling device and remain in operated condition until the calling device reaches its normal position. The springs 465 and 466 close a shunt circuit around the lower left-hand winding of repeating coil RC2 and shunt springs 467 and 468 complete a shunt circuit around the upper winding of relay 470 to improve the impulsing circuit. This shunt circuit may be traced from the left-hand terminal of the upper winding of relay 75

470 through springs 461, shunt springs 468 and 467, key springs 463, to the right-hand terminal of relay 470. The impulse springs 469 of the calling device are now connected in bridge of the 5 trunk as follows: through key springs 462, impulse springs 469, shunt springs 468 and 467, and key springs 463.

In response to the operation of the impulse springs 469 the circuit extending over the control 10 trunk to relays 301 and 302 is opened for each impulse of the digit dialled. Line relay 302 de-energizes for each impulse and at armature 318 completes the impulsive circuit to the series relay 311 and the vertical magnet 111 in multiple as 15 follows: from ground by way of armature 318 and resting contact, armature 323, armature 348, where the circuit divides, one branch extending through the winding of slow-to-release series relay 311 to battery, and the other branch extending by 20 way of armature 353 and resting contact, conductor 199, armature 130 and through the winding of vertical magnet 111 to battery. Relay 311, being slow to release, is maintained energized throughout the impulsive period and at armature 25 349 short circuits the right-hand winding of repeating coil RC1 by way of conductor 266 and armature 441. At armature 350 relay 311 disconnects ground from conductor 199 and at the working contact of armature 350 completes a circuit 30 for energizing relay 312 by way of armature 352 and resting contact. At armature 351 relay 312 completes a short circuit around relay 313 as follows: from ground by way of armature 350 and working contact, armature 352 and resting contact, through the winding of relay 313, armature 351 to the grounded lock conductor 390.

Vertical magnet 111 raises the wipers 151 to 154, inclusive, one step for each impulse received, thereby stepping the wipers of the local connector 40 opposite the level of bank contacts terminating the called line. On the first vertical step of the wipers vertical off-normal springs 125 grounds the guard conductor 65 and opens the original energizing circuit of relays 103 and 104 now held 45 energized from armature 112. Vertical off-normal springs 122 operate on the first vertical step of the wipers to open a further point in the circuit for grounding the chain conductor 69. Vertical off-normal springs 121 also operate on the first vertical 50 step of the switch wipers to open the circuit to the release magnet 109.

After the impulsive period slow-to-release series relay 311 deenergizes and at armature 350 opens the short circuit around the winding of the relay 55 313 with the result that relay 313 energizes in series with relay 312 from grounded lock conductor 390. At armature 352 relay 313 opens the original energizing circuit of relay 312 now held energized in series with relay 313 and at its working contact prepares the circuit for relay 314. At armature 353 relay 313 transfers the impulsive circuit from the vertical magnet 111 to the rotary magnet 110 and at armature 354 prepares a point 60 in a circuit to the supervisory motor magnet 461.

In response to the second series of impulses dialled line relay 302 again deenergizes for each impulse and upon each deenergization transmits an impulse to the series relay 311 over the previously traced circuit and also to the rotary magnet 70 75 as follows: from ground by way of armature 318 and resting contact, armature 323, armature 348, armature 353 and working contact, terminal 9, the dotted line connecting terminal 9 to terminal 10, conductor 195, armature 134 and rotary magnet 110 to battery. The rotary magnet 110 rotates

the wipers of the local connector to the bank contacts terminating the called line. Series relay 311 again energizes during the impulsive period and at armature 350 disconnects ground from conductor 189 and wiper 152 during the 5 rotary movement and at the working contact of armature 350 completes a circuit for energizing relay 314 as follows: from ground by way of armature 350 and working contact, armature 357, and through 10 the winding of relay 314 to battery. At armature 356 relay 314 closes a short circuit around the winding of relay 315 from grounded lock conductor 390 and grounded armature 350. After the impulsive period series relay 311 deenergizes and 15 at armature 349 removes the short circuit from around the repeating coil RC1. At armature 350 relay 311 grounds conductor 189 to complete a circuit for energizing the cut-off relay, such as cut-off relay 12, of the called line and at its working contact removes the short circuit from around relay 315 to allow relay 315 to energize in series with relay 314. The circuit for energizing relay 315 extends from grounded lock conductor 390 through armature 356 and working contact, and 20 25 through the winding of relays 315 and 314 in series to battery. At armature 357 relay 315 opens points in the original circuit of relay 314 and at armature 358 completes the circuit for energizing the monitoring relay 307 as follows: from 30 ground by way of armature 359 and resting contact, conductor 189, armature 129, wiper 152, the test bank contact of the called line and through the winding of the cut-off relay similar to cut-off relay 12 to battery. The cut-off relay of the called line, upon energizing at its upper armature, corresponding to 40 armature 16, opens the circuit to the line relay, at its lower armature, corresponding to armature 18, opens a point in the start circuit, and at its middle armature, corresponding to armature 17, grounds the corresponding finder connector bank to make 45 the called line busy to the finder switches.

Monitor relay 307, upon energizing, at armatures 329 and 331 disconnects the talking conductors extending to the calling line from conductors 268 and 269 and connects the talking 50 conductors 268 and 269 to the negative and positive ring conductors 181 and 188 to provide a listening circuit over which the control operator can determine if the called line is idle or busy. The control operator is now connected in a talking 55 circuit with the called line over the circuit extending from the contacts of the called line, wipers 151 and 154, armatures 128 and 136, negative and positive ring conductors 187 and 188, working contacts and armatures 329 and 331, 60 conductors 268 and 269, through the right-hand winding of repeating coil RC1. The voice currents are induced through the left-hand windings of repeating coil RC1 over trunk conductors 451 and 452 to the right-hand windings of the 65 repeating coil RC2 in the remote operating center from where the voice currents are repeated through the left-hand windings of repeating coil RC2 through the key springs 460 and 464 to the operator telephone circuit. If the called line is 70 busy and is one of a group of lines having the same called number, the operator dials the digit 1 causing the rotary magnet 110 to advance the wipers of the connector to the next line and again listens. The operator continues to dial 75

the digit 1 until an idle line or the last line in the group is reached. In case the operator does not hear any conversation she will then challenge to determine if the line is in use. If the operator receives no response she will then code ring the desired called subscriber.

In case the line is busy the operator will momentarily operate the two-way key to monitor position to cause the energization of differential relay 301 in the common equipment. In response to the operation of the two-way key to monitor position the lower winding of differential relay 301 is short circuited with the result that this differential relay now energizes. The circuit for short circuiting the lower winding of relay 301 may be traced as follows: from ground by way of the monitor springs, key springs 463, lower right-hand winding of repeating coil RC2, conductor 452, lower left-hand winding of repeating coil RC1, conductor 271, through the lower winding of differential relay 301 and through the lower winding of line relay 302 to ground. Line relay 302 is held energized over its upper winding and differential relay 301, upon energizing, at armature 316 grounds conductor 275 to complete a circuit for energizing relay 303 by way of armature 434 and working contact, conductor 274, armature 321 and resting contact, and through the winding of relay 303 to battery. At armature 319 relay 303 short circuits relay 304 from ground extending by way of armature 316 over the previously traced circuit to armature 321 and resting contact, through the winding of relay 304 and armature 319 to grounded lock conductor 390. Upon restoration of the two-way key to its normal position the short circuit around the lower winding of differential relay 301 is removed with the result that differential relay 301 now deenergizes. At armature 316 relay 301 disconnects ground from conductors 275 and 274 to remove the short circuit from around relay 304 whereupon the latter relay now energizes in series with relay 303 from grounded lock conductor 290. At armature 321 relay 304 opens the original energizing circuit of relay 303 and at its working contact prepares the circuit for ringing relay 308, and at armature 320 opens the circuit of monitor relay 307. Relay 307 deenergizes and at armatures 329 and 331 reconnects the talking conductors 268 and 269 associated with the control trunk to the talking conductors of the calling line. The control operator now informs the calling party that the called line is busy.

In case the called line is idle the control operator operates the key to monitor position with the result that relays 301, 303, 304 and 307 operate as just described. The control operator now operates the two-way key to ringing position in accordance with the code ring of the called subscriber. Differential relay 301 is operated once for each key operation to ringing position and grounds the conductors 270 and 271 of the control trunk previously described. Upon each energization of differential relay 301 that relay at armature 316 grounds conductors 275 and 274 by way of armature 434 from whence the circuit extends by way of armature 321 and working contact, terminal 6, dotted line, terminal 5, and 70 through the windings of ringing relay 308 and relay 309 in multiple to battery. Ringing relay 308 is energized each time the key is operated to ring position while the slow to release relay 309 is operated during the ringing period. Each time ringing relay 308 is energized ringing circuit

for ringing the called subscriber is completed at armatures 338 and 341 as follows: from the generator lead by way of conductor 75, working contact and armature 338, terminal 1, dotted line, terminal 2, conductor 187, armature 128, wiper 151 in engagement with the bank contact of the called line over the called subscriber's line through the wringer, over the positive line conductor, to wipers 154, armature 136, conductor 188, terminal 3, dotted line, terminal 4, armature 341 and working contact, to generator return conductor 76. At armature 335 ringing relay 308 prepares a circuit for relay 106 used in reverting and toll calls, at armature 333 completes an obvious circuit for energizing relay 310, and at armatures 336 and 339 completes the ring-back tone circuit for both the calling subscriber and the control operator. The ring-back tone circuit for the control operator extends from generator lead, conductor 75, tone condenser C, armature 336, to conductor 268, and thence over the previously traced circuit through the repeating coil RC1 back to conductor 269, and from thence by way of armature 339, tone condenser C' to generator return conductor. The ring-back tone to the calling subscriber may be traced from the tone condenser C, armature 336 and resting contact, conductor 185, armature 127, armature 143, armature 115, through the previously traced loop of the calling line to conductor 73, armature 119, armature 141 and resting contact, armature 137, conductor 186, armature 331, armature 339, to the tone condenser C'.

If, in a previous connection, another connector is in engagement with the bank contacts of the called line, because of failure of the subscriber to ring off that connection, then the first pulse of generator applied to the called line causes the energization of the A. C. relay 107 in this other connector to cause its release. The circuit for energizing relay 107 in this connector may be traced from the negative bank contacts of the called line and thence by way of wiper 151, armatures 144 and 138, the upper left-hand winding of repeating coil RC, through the winding of relay 107, the lower left-hand winding of repeating coil RC, armature 146, wiper 154, and positive bank contact of the called line. Relay 107 of the non-released connector at armature 148 completes the circuit for energizing release relay 102 which causes the release of this other connector in a manner to be described more fully herein-after.

Relay 309, due to its slow to release characteristics, is maintained energized during the ringing period and at armature 343 connects ground through both the left-hand windings of repeating coil RC3 to connect ground to the negative and positive ring conductors 187 and 188 at the time ringing relay 308 is in deenergized position in order to discharge the ringing condensers associated with the called line. At armature 342 relay 309 disconnects the right-hand winding of repeating coil RC3. Relay 310, upon energizing, at armature 345 prepares a point in the three-way talking circuit between the calling subscriber, the called subscriber, and the control operator, at armature 346 prepares a point in the talking circuit and for enabling ground at armature 343 to discharge the ringing condensers associated with the called line, at armature 335 prepares a point in the circuit to the cut-through relay 105, at armature 347 completes a locking circuit for itself from grounded armature 327, and at armature 348 opens a point in the impulsing circuit.

- Each operation of the two-way key to ringing position therefore causes the energization of differential relay 301 and ringing relay 308 to ring the called subscriber in accordance with his code. 5 An interval after the ringing period relay 309 de-energizes and at armature 342 completes a three-way talking circuit between both subscribers and the control operator as follows: The talking circuit between the calling subscriber and the control operator is the same as previously traced. A branch of this circuit extends from conductors 268 and 269 through the right-hand windings of the repeating coil RC3. Voice currents are induced into the left-hand windings of repeating coil RC3 and thence by way of the heavy talking conductors, armatures 338 and 341, conductors 187 and 188, armatures 128 and 136, wipers 151 and 154, and over the line conductors of the called line to the substation circuit. 10 15 20 25 30 35 40 45 50 55 60 65 70 75

The control operator either waits until the called subscriber answers or may disconnect from the control trunk and release the common equipment without waiting for the called subscriber to answer. Assuming that the control operator waits until the called subscriber answers, then when the operator is satisfied that the desired party has responded she will restore the key K to cause the release of the common equipment which in so doing establishes a new talking circuit between the calling and called subscribers. In response to the restoration of the key K, springs 460 and 464 disconnect the operator's telephone circuit and springs 462 and 463 reconnect both windings of relay 470 and the resistance R in bridge of the conductors 270 and 271 to cause the deenergization of line relay 302. Line relay 302, upon deenergizing, at armature 318 opens the circuit to slow release relay 305. Relay 305 de-energizes after an interval and at the working contacts of armature 322 disconnects ground from conductor 278 and opens the circuit of relay 306 and at its resting contact momentarily grounds the cut-through conductor 191 to cause the energization of relay 105. At armature 326 relay 305 disconnects ground from conductor 264 to de-energize test relay 207 and relay 431. Relay 207, upon deenergizing, at armature 228 prepares the circuit for motor magnet 64, at armature 231 opens a further point in its own locking circuit, and at armature 232 grounds conductor 273 to prepare the circuit for relay 203. Relay 431, upon deenergizing, at armature 434 disconnects conductors 274 and 275, at armature 441 disconnects conductors 266 and 268, at armatures 435 and 436 reconnects the supervisory switch to conductors 268 and 269, at armature 438 opens a point in its own locking circuit, and at armature 437 prepares a point in the circuit to relay 430. 20 25 30 35 40 45 50 55 60 65 70 75

The circuit for energizing cut-through relay 105 in response to the deenergization of relay 305 may be traced as follows: from ground by way of armature 322 and resting contact, armature 325, armature 355 and working contact, cut-through conductor 191, armature 131 and through the winding of cut-through relay 105 to battery. At armatures 133 and 142 relay 105 connects the right-hand windings of repeating coil RC to the calling line, at armature 138 connects the left-hand windings of repeating coil RC to the called line, at armature 139 grounds wiper 152 to maintain the cut-off relay 12 of the called line in energized position, at armature 140 completes a locking circuit for itself from grounded armature 112, and also opens the circuit of relay 104 which deenergizes, at armature 141 prepares a 20 25 30 35 40 45 50 55 60 65 70 75

circuit for relay 102, at armature 155 disconnects direct ground from conductor 68 and substitutes ground through the winding of marginal relay 170 for holding the cut-off relay 12 of the calling line in operated position, and at armature 145 prepares a circuit used in toll connections. Relay 104, upon deenergizing, at its armatures disconnects the common equipment from the local connection. The calling and called subscribers are now connected over the following talking circuit: from the calling line over the previously traced heavy talking conductors to armatures 115 and 119, and thence by way of armatures 143 and 147 and their resting contacts, armatures 133 and 142, to the right-hand winding of repeating coil RC. The called subscriber is connected over the talking conductors of his line to wipers 151 and 154 and thence by way of armatures 144, 138 and 146 through the left-hand windings of repeating coil RC. Voice currents are induced through the windings of the repeating coil RC thereby enabling the calling and called subscribers to converse with each other. 20 25 30 35 40 45 50 55 60 65 70 75

Slow-to-release relay 306 deenergizes an interval after its circuit is opened by the deenergization of relay 305, and at armature 325 opens the original energizing circuit of cut-through relay 105, which is now locked in energized position. At armature 327 relay 306 disconnects ground from the tone start lead and from the lock conductor 390 to cause the deenergization of relays 303, 304, 310, 312, 313, 314, and 315. At armature 328 relay 306 disconnects ground from the ringing machine start lead RMST and grounds conductor 264. At armature 330 relay 306 prepares a circuit for relay 203, and at armature 332 grounds conductor 277 and wiper 403 of the supervisory switch. The common equipment is now released and may be used on another call. 20 25 30 35 40 45 50 55 60 65 70 75

After conversation and in response to the calling subscriber ringing off, relay 108 is energized over the previously traced talking circuit to the calling line. If the called subscriber rings off relay 107 is energized over the previously traced talking circuit to the called line. In response to the energization of either relay 107 or 108 the circuit for energizing relay 102 is completed at armature 148 or 149, from ground at armature 141. Relay 102, upon energizing, at armature 113 connects a multiple ground to relays 103 and 105 to hold the same energized and at armature 114 grounds conductor 74 and completes an obvious circuit for energizing relay 101. Relay 101 at armature 112 disconnects one of the multiple grounds holding relays 103 and 105 in energized position. After ringing off relays 107 and 108 deenergize and open the circuit of relay 102. Relay 102, upon deenergizing, at armature 113 opens the circuit of relay 105 and 103 which now deenergizes and at armature 114 opens the circuit to slow-to-release relay 101 which deenergizes after an interval. Relay 105, upon deenergizing, at armatures 133 and 142 disconnects the right-hand windings of the repeating coil RC, at armature 138 disconnects the left-hand windings of repeating coil RC, at armature 139 disconnects ground from wiper 152 to deenergize the cut-off relay 12 of the called line, at armature 140 opens a point in its own locking circuit and prepares the circuit for relay 104, and at armature 141 opens the circuit of relay 102. Relay 103, upon deenergizing, at armatures 115 and 119 opens the circuit to the calling line, at armature 145 prepares a circuit used in toll connections. Relay 104, upon deenergizing, at its armatures disconnects the common equipment from the local connection. The calling and called subscribers are now connected over the following talking circuit: from the calling line over the previously traced heavy talking conductors to armatures 115 and 119, and thence by way of armatures 143 and 147 and their resting contacts, armatures 133 and 142, to the right-hand winding of repeating coil RC. The called subscriber is connected over the talking conductors of his line to wipers 151 and 154 and thence by way of armatures 144, 138 and 146 through the left-hand windings of repeating coil RC. Voice currents are induced through the windings of the repeating coil RC thereby enabling the calling and called subscribers to converse with each other. 20 25 30 35 40 45 50 55 60 65 70 75

tures 117 prepares a point in the chain circuit to the all link busy relay 208, at armature 118 opens a point in its own locking circuit, at armature 116 opens the circuit to the cut-off relay 12 of the calling line which deenergizes, and at armature 120 completes the circuit for energizing release magnet 109. Slow-to-release relay 101 deenergizes after an interval and therefore deenergizes after relays 103 and 105 have completely deenergized. In response to the operation of the release magnet 109 the switch wipers are restored to their normal positions in the well known manner. Off-normal springs 121 open in response to the wipers reaching their normal position to open the circuit to release magnet 109. In response to the restoration of off-normal springs 125 ground is removed from guard-lead 65 to make this local connector switch selectable and to prepare circuits to relays 103 and 104. The restoration of off-normal springs 122 grounds the chain start conductor 69 to maintain the all link busy relay 208 in energized position. In the calling line circuit the cut-off relay 12 deenergizes; at armature 16 reconnects the line relay 11, and at armature 18 reconnects the start conductor 30. In the called line circuit the cut-off relay deenergizes and reconnects the line relay and start conductor in a similar manner. The entire connection is now released and may be used for another call.

In case the control operator found the called line busy the control operator would operate her two-way key to its monitor position to disconnect from the called line and connect the control trunk to the calling line. In response to the operation of the key to monitor position the control trunk conductors 451 and 452 are grounded with the result that differential relay 301 energizes as before. At armature 316 relay 301 again completes the circuit for energizing relay 303 and the latter relay at armature 319 prepares the circuit for relay 304. The key is now released from its operated monitor position to its normal position, thereby causing the deenergization of differential relay 301. Relay 301, upon deenergizing, at armature 316 removes the short circuit from around relay 304 to allow the latter relay to energize in series with relay 303. At armature 320 relay 304 opens the circuit of monitor relay 307 to cause the latter relay to deenergize. Relay 307, upon deenergizing, at armatures 329 and 331 reconnects the control trunk to the calling line. The control operator now informs the calling subscriber that the line is busy and then restores the key K. In the same manner as previously described the restoration of the key K causes the deenergization of relays 302 and 305. The deenergization of relay 305 at this time, since the ringing operation has been omitted, completes a circuit for energizing release relay 102 in the local connector as follows: from ground by way of armature 322 and resting contact, armature 325, armature 355 and resting contact, release conductor 196, armature 135 and through the winding of relay 102 to battery. Relay 102 energizes and causes the release of the local connector in the same manner as previously described. In the common equipment relays 305 and 306 deenergize and release the common equipment in the same manner as previously described.

Reverting calls

In making a reverting call the calling subscriber will initiate the call in the same manner as previously described. When the control operator an-

swers in response to the signal and is informed that another subscriber on the same line is desired, the operator will inform the calling subscriber to replace his receiver. The control operator then operates the two-way key to monitor position and then to ringing position in accordance with the called subscriber's code without dialling any digits. The finder F, the distributor, and relays 103 and 104 in the local connector are energized in the same manner as previously described. The operation of the two-way key to monitor position grounds control trunk conductors 451 and 452 and conductors 270 and 271 to cause the energization of differential relay 301 as previously described. The operation of differential relay 301 at armature 316 completes the circuit by way of conductors 275 and 274 for energizing relay 303. When the key is released from its monitor position differential relay 301 deenergizes and removes the short circuit from around relay 304 whereupon the latter relay now energizes in series with relay 303 as previously described. The operator now operates the two-way key to ringing position in accordance with the called subscriber's code, thereby operating differential relay 301 each time the key is operated to ringing position. Each time differential relay 301 is energized ringing relay 308 is correspondingly energized to ring back over the calling line. Relay 309 is energized in multiple with relay 308 and due to its slow to release characteristics is maintained in operated position during the ringing period. At armature 333 relay 308, upon first energizing, completes the circuit for relay 310 which accordingly energizes and locks to lock conductor 390. At armature 335 ringing relay 308, upon first energizing, completes the circuit for energizing relay 106 in the local connector as follows: from grounded lock conductor 390, armature 356 and resting contact, armature 335, conductor 192, armature 132 and through the winding of relay 106 to battery. At armatures 338 and 341 relay 308 completes the ringing circuit to the calling line as follows: from direct generator, conductor 75, working contact and armature 338, terminal 1, the dotted line, terminal 2, conductor 187, armature 128, working contact and armature 143, armature 115, conductor 72, wiper 60, conductor 22 over the calling line to conductor 23, wiper 62, conductor 73, armature 119, armature 147 and working contact, armature 136, conductor 188, terminal 3, the dotted line, terminal 4, armature 341 and working contact, back to generator return lead 76. Relay 106, upon energizing, at armatures 144 and 146 disconnects the left-hand windings of the repeating coil RC, and at armatures 143 and 147 completes a point in the previously traced ringing circuit to the calling line. Relay 309, upon energizing, at armature 343 discharges the ringing condensers on the calling line during the silent period when ringing relay 308 is in deenergized position. When the calling and called parties answer the operator releases the key K, whereupon relays 302 and 303 deenergize in the same manner as previously described. At armature 322 relay 305 completes the following circuit for cut-through relay 105 in the local connector as follows: from ground by way of armature 322 and resting contact, armature 325, armature 355 and working contact, conductor 191, armature 131, and through the winding of relay 105 to battery. At armature 326 relay 305 opens the circuit to relays 207 and 431 to cause their deenergization and at armature 322 and working contact opens the circuit to relay 105. Re-

lay 105, upon energizing at armature 140 again completes its locking circuit and also opens the circuit of relay 104 to deenergize the latter relay. At armatures 133 and 142 relay 105 prepares circuits for connecting the right-hand winding of repeating coil RC to the calling line. Relay 104, upon deenergizing, disconnects the local connector from the common equipment, and at armature 132 opens the circuit to relay 106. Relay 106, upon deenergizing, at armatures 143 and 147 and resting contacts, connects the right-hand winding of the repeating coil RC to the calling line. In the common equipment relay 306 de-energizes after an interval and at armature 327 15 opens the circuit of relays 303, 304, 310 and 106. After conversation and in response to either the calling or called subscriber ringing off, relay 108 is energized over the calling line, and at armature 149 completes the circuit from grounded 20 armature 141 for energizing release relay 102. At armature 114 relay 102 completes the circuit for energizing relay 101 and at armature 113 closes a multiple ground circuit through all relays 103 and 105 in operated position. Relay 101, upon energizing, at armature 112 opens one of the multiple grounds to relays 103 and 105. After ringing off relay 108 deenergizes and at armature 149 25 opens the circuit to relay 102 which deenergizes. At armature 113 relay 102 opens the circuits of relays 103 and 105 which accordingly now de-energize, and at armature 114 opens the circuit of relay 101 which likewise deenergizes after an interval. Relay 103, upon deenergizing at armatures 133 and 142 disconnects the repeating coil 30 RC from the calling line. Relay 103, upon de-energizing, at armature 118 prevents the reapplication of ground to the guard lead 65 which ground was removed therefrom in response to the deenergization of relay 102. At armature 117 35 grounds the chain lead 69 to maintain relay 208 in operated position and at armature 116 disconnects ground through the winding of marginal relay 170 from conductor 68 to deenergize the cut-off relay 12 of the calling line. Cut-off relay 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

completes an energizing circuit for slow to operate relay 52, and at armatures 92 and 94 momentarily completes an energizing circuit through the upper winding of line relay 31 as follows: from ground by way of armature 92 and working contact, resting contact and armature 96, armature 36, upper winding of line relay 31, armature 35, armature 97 and resting contact, armature 94, and through the resistance 99 to battery. 5 10

Line relay 31, upon energizing, at armature 33 connects the calling potential through the winding of cut-off relay 32 to the finder bank, at armature 34 locks to start conductor 30 and causes the energization of start relay 201, and at armature 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

Common battery subscribers' lines can also be connected to this type of R. C. X. exchange by the use of a line adapter such as shown in Fig. 1 comprising relays 50 to 56, inclusive. When a common battery subscriber, such as indicated by S, removes his receiver, relay 50 is energized over the calling loop as follows: from ground by way of the lower winding of relay 50, resting contact and armature 56, armature 58 and resting contact, the calling substation loop, armature 55 and resting contact, armature 57 and resting contact, and through the upper winding of relay 50 to battery. At armatures 90 and 91 relay 50 disconnects the AC relays 53 and 54 at the resting contacts and at the working contacts thereof prepares points in the talking circuit. At armature 59 relay 50 completes an energizing circuit for slow to release relay 51. At armature 93 relay 51

In case a common battery line is being called the operation is the same as previously described. In case the called common battery subscriber's ringer is bridged across the line conductors or connected to the upper negative line conductor and ground then ringing current is applied to conductor 39 as previously described, and extends by way of armature 90 and resting contact through the winding of A. C. relay 53 to ground. A. C. relay 53 is energized over this circuit and at armatures 57 and 58 and resting contacts disconnects relay 50, thereby reducing the impedance to improve the ringing circuit over the called line. At armatures 57 and 58 and their

working contacts A. C. relay extends the ringing circuit by way of armature 55 and through the substation ringers to ground at armature 58 in case the ringers are bridged across the line or 5 through the ringers to ground at the substations in case the ringers are connected to the negative line conductor and ground at the substations. When the called subscriber answers the previously traced circuit is completed for energizing relay 10 50 during the first silent period when relay 53 is deenergized. Relay 59 at armatures 90 and 91 completes the talking circuit and at armature 59 energizes relay 51. Relays 51 and 52 energize in the same manner as previously described but in 15 this case, since the cut-off relay 32 was energized when the line was seized, line relay 31 does not energize in response to the momentary connection of ground and battery to the line conductors. After conversation and in response to the replacement 20 of the receiver relays 50, 51 and 52 deenergize as previously described to momentarily complete the circuit for energizing the relay, such as relay 107, in the local connector to cause the release thereof by the momentary connection of ground and battery to the conductors 39 and 40. In case the ringer of the called subscriber is connected to the bottom positive line conductor then 25 ringing current is connected to conductor 41 in a manner hereinafter described for divided ringing. In this case ringing current extends by way of armature 91 and resting contact and through the winding of A. C. relay 54 to ground to cause this relay to energize for each application of ringing current to conductor 41. At armature 56 relay 54 completes a circuit extending by way of 30 resting contact and armature 58 for ringing the ringers connected to positive line conductor and ground. During a silent period and when the called subscriber answers relay 50 is energized 35 over the called line to complete the talking circuit as previously described.

Toll calls

In order to complete a toll call to a subscriber 40 in the R. C. X. the toll operator inserts a plug of a cord circuit into the jack J. In response to the insertion of the plug into the jack J springs 521 complete a circuit for energizing relay 503 as follows: from ground through the lower winding of 45 relay 503, lower winding of differential relay 504, lower left-hand winding of repeating coil RC5, resting contact and armature 521, conductor 591, lower right-hand winding of repeating coil RC4, jack springs 521, upper right-hand winding of 50 repeating coil RC4, conductor 590, armature 525 and resting contact, upper left-hand winding of repeating coil RC5, upper winding of differential relay 504, and through the upper winding of line relay 503 to battery. Line relay 504 energizes 55 over the above traced circuit but differential relay 504 does not energize because its windings are equal and oppose each other. At armature 531 relay 503 completes an obvious circuit for energizing slow-to-release relay 502. At armature 528 relay 502 prepares a circuit for the upper winding of relay 503, at armature 529 completes a circuit for energizing relays 506 and 508, as follows: from ground by way of armature 529 and working contact, normally closed springs controlled by armature 538, armature 545 and resting contact, and through the windings of relays 506 and 508 in multiple to battery. At armature 534 relay 506 short circuits the right-hand winding of repeating coil RC5 to prevent noises in 70 the operator's head-set. Relay 508, upon energi-

gizing, at armatures 541 and 542 complete the circuit for energizing line relay 511 of the toll line circuit as follows: from ground by way of resting contact and armature 537, working contact and armature 542, armature 563, upper winding 5 of relay 511, armature 564, armature 541 and working contact, armature 536 and resting contact, and through resistance 535 to battery. At armature 543 relay 508 completes an obvious circuit for energizing the slow-to-operate relay 507. 10 Relay 511, upon energizing at armature 561 connects calling potential through the windings of both relay 509 and 512 to the finder banks by way of conductor 165. At armature 562 locks itself over the common start lead 30 and also energizes 15 the start relay 201, and at armature 563 opens a point in its original energizing circuit after its locking circuit has been completed. Slow-to-operate relay 507 energizes after an interval and at armatures 536 and 537 opens the original energizing circuit of line relay 511 and connects generator to the contacts 581 and 582 to release any connector having its wipers in engagement with such contacts. At armature 538 relay 507 completes a locking circuit for itself from grounded 20 armature 529 and also opens the circuits of relays 506 and 508 which deenergize after an interval. Relay 508, upon deenergizing, at armatures 541 and 542 disconnects generator from conductors 161 and 164 and the bank contacts 581 25 and 582, and connects the right-hand winding of repeating coil RC5 to conductors 161 and 164. At armature 543 relay 508 opens the original energizing circuit of relay 507. Relay 506, upon deenergizing, at armature 534 removes the short 30 circuit from around the right-hand winding of repeating coil RC5.

The operation of the start relay 201 causes the finder to find the toll trunk in the same manner as previously described, whereupon relays 509 and 512 energize in series with relays 206 and 207 as follows: from grounded conductor 260, armature 223, lower winding of relay 206, upper winding of test relay 207, wiper 258, conductor 68, wiper 61, fourth bank contact, conductor 165, armature 45 561, where the circuit divides, one branch extending to the cut-off relay 512 to battery and the other branch extending by way of armature 544 and resting contact through the winding of relay 509 to battery. Relay 512, upon energizing, at armature 564 disconnects line relay 511, at armature 565 maintains its own circuit and the circuit to relay 509 independent of armature 561, and at armature 566 opens the start circuit to relays 201 and the locking circuit of relay 511. 55 Line relay 511 accordingly deenergizes and at armature 563 prepares a point in the talking circuit. Relay 509, at armature 546, opens the circuit to relay 510 to prevent the toll line being called. The control operator is signalled in the 60 same manner as described for a local call and thereupon answers such call by operating the key K. A talking circuit between the toll operator and the control operator may be traced as follows: from the toll operator's head-set and cord circuit, jack springs 522 and 523, repeating coil RC4, conductors 590 and 591, armatures 525 and 527 and their resting contacts, repeating coil RC5, resting contact and armatures 541 and 542, armature 563, conductors 161 and 164, wipers 60 and 70 62 of the finder G, assuming the finder F and the local connector in Fig. 2 to be the finder connector link taken into use on this call, conductors 72 and 73, armatures 115 and 119, armatures 143 and 147 and their resting contacts, 75

armatures 127 and 137, conductors 185 and 186, resting contacts and armatures 329 and 331, conductors 268 and 269, repeating coil RC1, conductors 451 and 452, repeating coil RC2, key springs 5: 460 and 464 to the control operator's heat-set.

Upon response of the control operator the toll operator informs the control operator of the desired connection. The control operator now dials the digits of the called number and operates the 10 associated local connector in the same manner as previously described. In response to dialling the digits of the called number relay 307 is energized to disconnect the calling toll line from the control trunk and connect the called line to 15 place thereof to enable the control operator to determine if the called line is busy or idle. In case the called line is idle the control operator will first operate the two-way key to monitor position to cause the energization of differential 20 relay 301 and relay 303 as previously described.

In response to the restoration of the key from monitor position differential relay 301 deenergizes and permits the energization of relay 304 in series with relay 303 as previously described. The operation of relay 304 causes the deenergization of relay 307, thereby again connecting the toll operator with the control operator. The control operator now operates the two-way key into ringing position in accordance with the code of the 30 called subscriber. Each time the key is operated to ring position differential relay 301 energizes and causes the energization of ringing relay 308 to signal the called subscriber in the manner previously described. When the called party 35 answers the control operator disconnects from the connection by restoring the key K, thereby causing the deenergization of relays 302 and 305 to energize cut-through relay 105 in the local connector as previously described. When relay 105 at 40 armature 155 removes the short circuit from around relay 170 the latter relay now energizes over the following circuit: from ground by way of the winding of relay 170, armature 116, conductor 68, wiper 61, conductor 165, armature 565, and in multiple through the windings of relay 512 45 and 509. Due to the increased battery potential through both windings of relays 509 and 512 marginal relay 170 energizes and transfers the control of the connection from the local subscriber 50 to the toll operator. At armature 171 relay 170 completes a circuit for energizing relay 102 from grounded armature 141 and at armature 172 completes a circuit for energizing relay 106 from 55 grounded armature 141. Relay 106, upon energizing, at armatures 143, 144, 146 and 147 disconnects the repeating coil RC and connects the conductor 72 and 73 direct to wipers 151 and 154, thereby completing a direct talking circuit between the toll operator and the called line independent of the repeating coil RC.

Relay 102, upon energizing, at armature 113 holds relays 103 and 105 energized, and at armature 114 completes the circuit for relay 101. Relay 101, at armature 156, places a partial shunt 60 including resistance 173 around the winding of relay 170, but does not cause its deenergization at this time. After conversation and in response to the called subscriber ringing off, ringing current extends over wipers 151 and 154, working 65 contacts and armatures 143 and 147, armatures 115 and 119, conductors 72 and 73, wipers 60 and 62, conductors 161 and 166, armature 563, armatures 541 and 542 and resting contacts, the right-hand winding of repeating coil RC5, and through 70 75 the winding of relay 505. Relay 505 energizes in

response to ringing current and at armature 533 completes the circuit for energizing relay 501. At armature 526 relay 501 completes a holding circuit through the upper winding of relay 503, and at armatures 525 and 527 and their working contacts connects generator and generator return to toll conductors 590 and 591 and from thence by induction through the repeating coil RC4 to the operator's cord circuit to give the toll operator disconnect supervision in the well known 10 manner.

The toll operator can rering the called subscriber by the operation of the ring key 524 which causes the energization of differential relay 504 since the lower winding of differential relay 504 15 is short circuited by the operation of key 524. This circuit may be traced as follows: from ground by way of springs 524, upper right-hand winding of repeating coil RC4, jack springs 521, lower right-hand winding of repeating coil RC4, conductor 591, armature 527 and resting contact, lower left-hand winding of repeating coil RC5 through the lower winding of differential relay 504 and through the lower winding of relay 503 to ground. This same ground extends over the 25 upper talking conductor by way of key 524, conductor 590, armature 525, upper winding of repeating coil and through the upper windings of relays 504 and 503 to maintain relay 503 in energized position. Since the lower winding of differential relay 504 is short circuited, relay 504 30 now energizes. At armature 532 relays 504 completes the circuit for energizing relays 506 and 508 in multiple. At armature 534 relay 506 again short circuits the repeating coil RC5 and relay 35 508, at armatures 541 and 542 connects direct generator and generator return to conductors 161 and 166 to rering the called subscriber. Each operation of key 524 therefore causes the energization of relay 504 and the energization of relay 40 508 to connect ringing current to the called line to rering the code of the called line.

In response to the receipt of the disconnect signal, the toll operator removes the plug from the jack J, thereby separating the jack springs 45 521 to open the circuit to relay 503. Relay 503, upon deenergizing, at armature 531 opens the circuit to relay 502 which deenergizes after an interval. At armature 529 and working contact relay 502 opens the circuit to relay 507 which 50 accordingly deenergizes and at the resting contact of armature 529 momentarily operates relay 510. Relay 510, upon energizing, at armature 544 grounds conductor 165 by way of armature 565 and maintains the cut-off relay 512 in operated 55 position. At armature 544 and resting contact relay 510 opens the circuit of relay 509 which accordingly deenergizes. After an interval relay 507 deenergizes and at armature 539 opens the circuit to relay 510 which accordingly deenergizes after an interval. In the local connector relay 170 is short circuited by the direct ground connected to conductor 165 by way of armature 544 to cause this relay to deenergize. After an interval relay 510 deenergizes and removes ground 60 from conductor 165 and opens the circuit of cut-off relay 512. In the meantime in the local connector relay 170 deenergizes and at armature 171 opens the circuit to relay 102 which deenergizes. At armature 172 opens the circuit to relay 106 65 which deenergizes. Relay 102, upon deenergizing, at armature 113 opens the circuit to relays 103 and 105 which accordingly deenergizes, and at armature 114 opens the circuit to relay 101 which deenergizes after an interval. At armature 70 75

ture 116 relay 103, upon deenergizing, opens the circuit to cut-off relay 512 and relay 512 deenergizes when relay 510 at armature 544 deenergizes to open the circuit thereto. The local connector 5 now releases in the same manner as previously described.

It will now be assumed that a local R. C. X. subscriber wants a toll connection. In response to the initiation of a call the local R. C. X. subscriber is connected to the control trunk and the control operator is signalled in the same manner as previously described. After answering the call the control operator then operates the connector to position the wipers opposite the level of toll lines in response to dialling the digits corresponding to the group of toll lines. Assuming the local connector in Fig. 2 to be the local connector in use, then when the wipers are raised opposite the toll level, normal post springs 157 close. The closure of normal post springs 157 prepares the circuit for relay 106. In the same manner as previously described the toll operator now rotates the wipers of the local connector to an idle toll line in the group. Assuming now that the toll line shown in Fig. 6 is the toll line taken into use, then when series relay 311 in the common equipment deenergizes after the dialling period and grounds the wiper 152 a circuit is completed for energizing relay 510 in the toll trunk as follows: from ground by way of armature 350 and resting contact, conductor 189, armature 129, wiper 152, bank contacts 583, conductor 162, armature 546, and through the winding of relay 510 to battery. At armature 544 relay 510 completes an obvious circuit for energizing the cut-off relay 512 of the toll line circuit and at armature 545 prepares the circuit of relay 507. Relay 512, upon energizing, at armature 555 connects ground by way of armature 544 to conductor 165 to busy this line in the finder banks. At armature 564 relay 512 disconnects line relay 511 and at armature 566 opens a point in the circuit to the start lead 30. The control operator now operates her two-way key to monitor position and then to ringing position to cause the operation of relays 301, 303, 314, and 308 as previously described. By the operation of ringing relay 308 ringing current is connected over the wipers 151 and 154 in the manner previously described and thence by way of armatures 541 and 542 and their resting contacts to the winding of relay 505. Relay 505 energizes and at armature 533 completes the circuit for energizing relay 501. At armatures 525 and 527 relay 501 connects ringing current over the toll trunk conductors 590 and 591 and through the repeating coil RC4 to operate the drop at the toll operator's position. After ringing the toll operator the control operator restores the two-way key to its normal position thereby interrupting the application of ringing current to the toll lines to cause the deenergization of relay 505. Relay 505, upon deenergizing, opens the circuit of relay 501 which likewise deenergizes. At armatures 525 and 527 relay 501 prepares the circuit for relay 503.

In response to the operation of the drop the toll operator inserts the plug of her cord circuit into jack J to open the drop and restore the same. At jack springs 521 a circuit is completed for energizing relay 503 as follows: from ground through the lower windings of relays 503 and 504, lower left-hand winding of repeating coil RC5, resting contact and armature 527, conductor 591, lower right-hand winding of repeating coil RC4, jack springs 521, upper left-hand winding of re-

peating coil RC4, conductor 590, armature 525 and resting contact, upper left-hand winding of repeating coil RC5 and through the upper windings of relays 504 and 503 to battery. At armature 531 relay 503 completes a circuit for energizing relay 502. At armature 529 relay 502 completes the circuit for energizing relay 507 as follows: ground by way of armature 529 and working contact, normally closed springs controlled by armature 538, armature 545 and working contact and through the winding of relay 507 to battery. At armature 538 relay 507 completes the locking circuit for itself from grounded armature 529. When the toll operator answers and is informed of the desired connection the control operator disconnects by restoring the key K to cause the operation of the cut-through relay 105 and the release of the common equipment as previously described. Relay 105, upon energizing, at armature 139 grounds wiper 152 to maintain relay 510 in operated position. At armature 140 completes the locking circuit for itself as well as opening the circuit of relay 104, at armature 141 completes a circuit for energizing relay 106 through the normal post springs 151, and at armature 145 prepares a point in the circuit to relay 102. Relay 106, upon energizing, disconnects the repeating coil and connects the calling subscriber direct to the toll line by way of wipers 151 to 154, inclusive.

After completion of the desired connection and when the calling local R. C. X. subscriber rings off, a circuit is completed for operating the relay 505 in the toll trunk as follows: ringing current extends from the calling subscriber over the heavy talking conductors to armatures 143 and 147 and their working contacts, wipers 151 and 154, connector banks 581 and 582, conductors 161 and 164, armatures 541 and 542 and their resting contacts, and through the right-hand windings of repeating coil RC5 and relay 505. Relay 505 at armature 533 completes the circuit for energizing relay 501 and the latter relay at armatures 525 and 527 connect ringing current from the direct generator source over the conductors 590 and 591 through the repeating coil RC4 to the toll operator's cord circuit to operate the supervisory disconnect signal in the well known manner. The toll operator in response to this disconnect signal is advised that the conversation is terminated, and if desired may re-ring the calling subscriber. In response to the operation of the supervisory signal the toll operator will remove the plug of her cord circuit from the jack J, thereby at jack springs 521 opening the circuit to relay 503. In response to the de-energization of relay 503, relay 502 deenergizes after an interval. At armature 529 and its working contact relay 502 opens the locking circuit of relay 507 and at its resting contact momentarily completes a holding circuit for relay 510 by way of armature 539 for the period of time it takes relay 507 to deenergize. Relay 507 in addition to being slow to operate is likewise slow to release. At armature 530 relay 502 momentarily grounds conductor 163 by way of armature 540 to complete an energizing circuit for release relay 102 in the local connector, as follows: from ground by way of armature 530, armature 540, conductor 163, bank contact 584, wiper 153, armature 145 and through the winding of relay 102 to battery. Relays 102 and 101 in the local connector energize in the same manner as previously described. In the toll trunk relay 507 deenergizes after an interval and at armature 540 opens the circuit

to relay 102. In response to the deenergization of relay 102 relays 103 and 105 deenergize. At armature 141 relay 105 opens the circuit of relay 106 which accordingly deenergizes and at armature 139 opens the circuit to relay 510 which likewise deenergizes in case armature 539 is now open. The local connector restores to its normal position in the same manner as previously described and the toll trunk and local connector 10 may thereafter be used in other calls.

The control operator is signalled at a time when all of the local connectors are busy either due to such connectors being actually in use, or due to the local subscribers failing to release the 15 same after disconnection. The all link busy relay 208 is normally energized over the chain conductor 69 which extends to all the local connectors and is connected to ground by way of armatures 117, off normal springs 122, and springs 124 of the 20 busy key in all the local connectors. When all of the local connectors are busy all of the ground connections are disconnected from conductor 69 with the result that the all link busy relay 208 deenergizes. Relay 208, upon deenergizing at 25 armature 234 prepares a point in the circuit for connecting the busy tone conductor to the control trunk, at armature 234 disconnects ground from the multipled bank contacts accessible to wiper 255 to provide stopping positions for the wipers 30 of the distributor, at armature 237 and working contact opens a point in the circuit to relay 203 and at its resting contact prepares a circuit through the lower winding of relay 211, and at armature 233 prepares a point in the circuit 35 through the upper winding of relay 209. When the operator releases after completing the call which took the last available idle local connector, relay 306, upon deenergizing completes a circuit for energizing relay 211 as follows: from 40 grounded conductor 262, armature 232 and resting contact, conductor 273, armature 330, conductor 281, armature 237 and resting contact, and through the lower winding of relay 211 to battery. The relay 211, upon energizing, at armature 248 connects the busy tone lead to conductor 268, at armature 250 completes a locking circuit through its upper winding from grounded 45 armatures 241 and 235, at armature 247 connects grounded armature 240 to conductor 269, at armature 251 completes an energizing circuit 50 through the lower winding of relay 207 and at armature 285 prepares a circuit for relay 209. At armature 231 relay 207 completes a locking circuit through its lower winding from grounded 55 conductor 264, at armature 229 opens a point in a circuit to motor magnet 401, at armature 232 and resting contact opens a point in the original energizing circuit of relay 211, and at its working contact completes the previously traced circuit 60 for energizing relay 430. In the same manner as previously described relays 430 and 431 operate to signal the control operator at the remote operating center. The control operator answers by operating the key K and receives busy tone indicating that all of the connectors are busy. The 65 busy tone circuit may be traced as follows: from the busy tone lead 223, armature 234, armature 238, resting contact and armature 244, armature 248, conductor 268, through the right-hand windings of the repeating coil RC1, conductor 269, armature 247, armature 243 and resting contact, to grounded armature 240. Busy tone is induced 70 into the left-hand windings of the repeating coil RC1, and thence over the control trunk conductors 451 and 452 to the operator's head-set,

In order to cut off the busy tone the operator dials the digit 1 and in the same manner as previously described line relay 302 follows the impulse received. Upon the deenergization of line relay 302 said relay at armature 318 and resting 5 contact completes a circuit by way of armatures 323 and 348 for energizing the series relay 311, and by way of armature 324, conductor 279, armature 285, armature 233 and resting contact completes a circuit through the upper winding of relay 209 to battery for energizing the latter relay. At armatures 238 and 240 relay 209, upon energizing, disconnects the busy tone from the control trunk, at armature 239 completes a locking circuit through its lower winding from grounded conductor 278, at armature 242 prepares a point in the circuit to motor magnet 401, at armature 252 opens a point in the original energizing circuit of relay 430, and at armature 289 opens the locking circuit of relay 431 to cause the latter relay 20 to deenergize. Series relay 311, upon energizing, at armature 350 and working contact, completes the energizing circuit for relay 312 which energizes and at armature 351 prepares the circuit 25 for relay 313. At the end of the impulse, series relay 311 deenergizes and at armature 350 and working contact removes the short circuit from around relay 313 whereupon relay 313 energizes in series with relay 312 from grounded lock conductor 390. Relay 313, upon energizing at armature 354 prepares the circuit for motor magnet 401 of the supervisory switch. Relay 430, upon deenergizing, at armatures 434, 435, and 436 connects the wipers of the supervisory switch to the common equipment. 30

In order to supervise the local connection and determine if the local connectors are in actual use the control operator now dials the digit 1 to step the wipers of the supervisory switch into engagement with the bank contacts terminating 40 the first local connector. When line relay 302 is deenergized in response to this impulse a circuit is closed by way of armatures 318 and 324, conductor 279, armature 242, conductor 280, armature 354, conductor 276, and through the 45 winding of supervisory motor magnet 401 to battery. In response to the energization and deenergization of motor magnet 401 the wipers of the supervisory switch are now operated into engagement with their first set of bank contacts, wiper 50 404 being connected to conductor 74, wiper 405 being connected to conductor 72, and wiper 406 being connected to conductor 73. Since relay 431 is not energized at this time the control 55 trunk is bridged directly across the talking conductors of the first local connector by way of armatures 435 and 436. The operator can now hear if any conversation is taking place and in case she does not hear any conversation she will challenge and if no response is given to her challenge she will operate either the two-way monitor and ring key. In case the first local connector is in use the operator will hear such conversation or will receive a response to her challenge. Since 60 this local connector is in use the control operator will again dial the digit 1 to reoperate relay 302 to cause the motor magnet 401 of the supervisory switch to step the wipers to the second local connector. The control operator continues to supervise all of the remaining local 65 connectors and releases all such connectors not in actual use in a manner to be described hereinafter. The rectifier 490 is bridged across the wipers 405 and 406 of the supervisory switch in order to prevent dial impulses from interfering 70 75

with or disturbing the existing connections encountered by the wipers of the supervisory switch.

After the operator challenges to make sure that the local connector engaged by the supervisory wipers is not in actual use she will then operate the two-way ring key to cause the energization of differential relay 301 as previously described. In response to the operation of differential relay 301, relay 101 in the local connector connected to the wipers of the supervisory switch is operated over the following circuit: from ground by way of armature 316, conductor 275, armature 434 and resting contact, wiper 404 in engagement with the bank contact terminating conductor 74 of the local connector in operated position but not in use, and from thence through the winding of relay 101 to battery. Relay 101 in the local connector, upon energizing, at armature 156 closes a partial short around the winding of relay 170 to cause the latter relay to de-energize, if energized, and at armature 112 opens the locking circuit of relays 103 and 105 to cause these relays to deenergize and release the local connector in the same manner as previously described. In a similar manner each local connector supervised by the control operator and not in actual use is released in this manner by the operator.

As soon as one of the local connectors becomes idle ground is connected to the chain lead 69 by such idle connector to cause the energization of all link busy relay 208. Relay 208, upon energizing, at armature 235 opens one of the multiple locking grounds to relay 211 and connects ground to the multiple bank contact accessible to wiper 255 to cause the distributor to hunt for the idle connector. At armature 237 relay 208 prepares a point in the circuit for relay 203 and at armature 233 prepares a point in the circuit to relay 280. The first time relay 302 deenergizes in response to an impulse after a connector becomes idle, relay 280 is energized over the following circuit: from ground by way of armature 218 and resting contact, armature 324, conductor 279, armature 285, armature 233, and through the winding of relay 280 to battery. This impulse of current, therefore, in addition to operating the wipers of the supervisory switch, also causes the operation of relay 280. At armature 241 relay 280 opens the locking circuit of relay 211, which accordingly deenergizes. Relay 211, upon de-energizing, at armature 251, opens the original energizing circuit of relay 207, so that the latter relay will restore when the operator disconnects from the control trunk. At armature 285 relay 211 opens the circuit to relay 280 to prevent the reenergization of relay 280. After supervising all of the local connectors the operator disconnects thereby opening the circuit of relay 302. Relay 302 and later relay 305 deenergize. At armature 322 relay 305, upon deenergizing, opens the circuit of relay 209 which accordingly deenergizes and at armature 326 disconnects ground from conductor 264 to cause the release of relay 207. In case the operator should disconnect without supervising the local connectors then relay 208 is maintained in its deenergized position. Relay 211 is maintained in energized position from armature 235 and resting contact. Relay 207 is maintained energized from armature 251. When relay 209 releases in response to the de-energization of relay 305 relay 430 is reoperated by way of armatures 232 and 252 to signal the control operator over the previously traced circuit. From the foregoing it will be seen that the

operator is repeatedly signalled as long as all of the local connectors are in use, and therefore the control operator must necessarily supervise the local connectors and release one or more connectors not in actual use.

In case a fuse blows, the battery charger fails, or a connector fails to release properly a relay group (not shown) is arranged to ground alarm conductor 236 in the well known manner customary in automatic systems. When conductor 236 is grounded a circuit is completed by way of armature 282 for operating relay 210. At armature 242 relay 210 prepares a circuit for connecting signalling current to conductor 268, at armature 246 completes a circuit for relay 211 in case relay 207 is not energized, at armature 245 opens a point in the circuit to relay 203. If no call is in progress relay 211 is energized over the following circuit: from ground by way of conductor 262, armature 232 and resting contact, conductor 273, armature 330, conductor 281, armature 246, and through the lower winding of relay 211 to battery. At armatures 248 and 241 relay 211 connects the generator conductor 75 by way of condenser M, working contact and armature 244 to conductor 268, and thence through the winding of repeating coil RC1 back to conductor 269 and thence by way of armature 247, armature 243 and working contact, to generator return conductor 76. Ringing current is induced into the left-hand winding of repeating coil RC1 in order to advise the operator, when she answers, of the trouble condition in the R. C. X. At armature 250 relay 211 completes a locking circuit for itself from grounded armature 241 and at armature 251 completes a circuit through the lower winding of relay 207 to energize the latter relay. Relay 207, upon energizing, at armature 231 completes its own locking circuit, and at armature 232 and its working contact completes the circuit for operating relay 430 to signal the control operator in the same manner as previously described. When the operator answers by throwing her key K, the generator signal as previously described is heard by the operator, thereby indicating trouble at the R. C. X. In order to remove the tone the operator disconnects by restoring her key K, thus opening the circuit to relay 302. Relay 302 opens the circuit to relay 305, but before relay 305 is deenergized the following circuit for relay 280 is completed from ground by way of armature 318 and resting contact, armature 324, conductor 279, armatures 285 and 284 and through the winding of relay 280 to battery. Relay 280 at armature 283 locks itself to the alarm conductor 236, at armature 282 opens the circuit of relay 210 which accordingly deenergizes and at armature 241 opens the locking circuit of relay 211. Relay 211, upon deenergizing, at armatures 248 and 247 disconnects the alarm tone from repeating coil RC1, at armature 285 opens the original energizing circuit to relay 280, and at armature 251 opens the original energizing circuit of relay 207. Relay 210, upon deenergizing, at armatures 244 and 243 opens a further point in the circuit connecting the alarm tone to the control trunk, at armature 246 opens the original energizing circuit of relay 211, at armature 245 prepares a circuit for relay 203. An interval after relay 302 deenergizes, relay 305 deenergizes and at armature 323 opens the circuit of relay 311, at armature 326 opens the circuit of relay 431 and the locking circuit of relay 207, and at armature 75

- 322 opens the circuit of relay 306. Relays 431 and 207 deenergize. When ground is removed from the alarm lead 236, the locking circuit of relay 289 is opened with the result that this relay 5 now deenergizes and at armature 282 connects the alarm lead to relay 210.

Divided ringing

- Referring to Fig. 4 and Fig. 4A, the circuit in 10 Fig. 4 may be converted so as to provide for divided ringing by the inclusion of the relays shown in Fig. 4A when the same are connected to corresponding terminals indicated by circles in Fig. 4. In this case the dotted lines shown in 15 Fig. 4 are cut and corresponding terminals connected together. The divided ringing relay group shown in Fig. 4A therefore provides means for signalling subscribers having their ringers connected from either line conductor and ground. 20 Since the operation of the system is the same for all calls except with regard to the ringing operation only a brief description of these operations will therefore be given. In order to provide the divided ringing the operator after dialling the 25 first two digits of the called subscriber's number will dial either the digit 1 or the digit 2 in order to select the line conductor over which ringing current is to be transmitted to ring the proper called subscriber thereon.
- 30 In response to the first deenergization of relay 302 in dialling the first digit of the called subscriber's number, said relay at armature 317 completes a circuit for energizing relay 701 from 35 grounded armature 311, armature 332 and working contact, terminal 7, armature 707 and resting contact, and through the winding of relay 701 to battery. At armature 706 relay 701 prepares a circuit for energizing relay 702 in series with relay 701, but relay 702 is short circuited from 40 ground on the lock conductor 390 by way of armature 359, terminal 8, armature 706, to ground at armature 311. At the end of the first impulse when relay 302 reenergizes ground is disconnected from terminal 7 whereupon the short circuit is 45 removed from relay 702 and relay 702 energizes in series with relay 701 from the grounded lock conductor 390. At armature 707 relay 702 opens the original energizing circuit of relay 701 and at the working contact of armature 707 prepares 50 the circuit for relay 703. In response to the second impulse of the first digit relay 703 is energized over the following circuit: from ground by way of armature 317, armature 332, terminal 7, armature 707, armature 710 and through the 55 winding of relay 703 to battery. In a similar manner relay 703 at armature 709 prepares the circuit for relay 704 but the latter relay is short circuited from grounded lock conductor 390 until relay 302 reenergizes and removes the short circuit from relay 704 at armature 317. Further 60 impulses of the first digit are ineffective so far as operating relays 701 to 704 are concerned, and these relays therefore remain locked in energized position to grounded lock conductor 390. In response to the second digit of the called number series relay 311 energizes and causes the energization of relay 314 which, at armature 359 opens the locking circuit of relays 701 to 704 to cause 65 such relays to deenergize. The reason relays 701 to 704 operate in response to the first digit dialled by the control operator is to enable the control operator to make a reverting call. In reverting calls the first digit dialled determines 70 the line conductor over which ringing current is 75 to be transmitted to the called subscriber. At the end of the second digit it will be remembered that series relay 311 falls back and causes the energization of relay 315 which at armature 361 prepares the locking circuit for relays 701 to 704, 8 inclusive. Except in reverting calls the next digit, or the third digit, dialled determines which line conductor of the called line ringing current is to be transmitted over. In case the third digit dialled is the digit 1 then relays 701 and 702 are 10 reenergized and locked to conductor 390 by way of armature 361. Relays 701 and 702 are the only relays energized for the digit 1 and in this case no circuit is prepared for the reversing ringing relay 705 with the result that when the ringing key is operated relay 308 is operated in the same manner as previously described over circuits this time extending from terminal 6, armature 711 and resting contact, terminal 5, and then to 15 ringing relay 308. Generator lead 75 is therefore connected over the negative wiper 151 to ring the subscribers having their ringers connected to the negative line conductor and ground. In case the digit 2 is dialled for the third digit, then 20 relays 701 and 702 are energized in response to the first impulse and relays 703 and 704 are energized in response to the second impulse as previously described. At armature 708 relay 704, upon energizing, prepares a circuit for the rotary magnet of the local connector to enable the control operator to step the wipers of the local connector one step at a time to locate an idle toll trunk. At armature 711 relay 704 prepares a circuit for the reversing relay 705 and at armature 711 and resting contact opens the circuit connecting terminal 6 to terminal 5. When the operator operates the two-way ring key in accordance with the code of the called subscriber, reversing relay 705 is operated in response to 25 each operation of differential relay 301 over the following circuit; from ground by way of armature 316, conductor 275, armature 434 and working contact, conductor 274, armature 321 and working contact, terminal 6, armature 711 and working contact, and through the reversing relay 30 705 to battery. At armature 712 and resting contact relay 705 disconnects terminal 2 from terminal 1, and at the working contact thereof connects terminal 2 to terminal 4. At armature 713 and resting contact relay 705 disconnects 35 terminal 3 from terminal 4 and at the working contact thereof connects the terminal 3 to terminal 1. The operation of armatures 712 and 713 therefore reverses the ringing connections. At armature 714 relay 705 completes the circuit 40 for operating the ringing relay 308 as follows: from ground by way of armature 714, terminal 5, and through the winding of ringing relay 308 to battery. Each time ringing reversing relay 705 energizes ringing relay 308 likewise energizes and completes the following circuit: from generator lead 75, working contact and armature 338, terminal 1, working contact and armature 713, terminal 3, conductor 188, armature 136, wiper 154, and over the positive line conductor of the called line to the ringers connected to this line conductor and ground. 45
- Whenever the control operator extends a connection to a toll trunk the control operator always 50 dials the digit 2 to prepare the circuit to reversing relay 705 and in addition to cause the operation of relay 704 which at armature 708 connects the terminal 10 to terminal 9 so as to enable the control operator to operate the rotary magnet of 55 60 65 70 75

the local connector in use to step the wipers thereof one step at a time in search of an idle toll line in a group.

Paystation tone

5 It will now be assumed that the calling subscriber is a paystation subscriber. Referring to the line circuit LC in Fig. 1, conductors 86 and 42 are only connected to the line circuit in case the 10 line is a paystation line. In this case it will be assumed that the subscriber's line shown in the upper left-hand corner is a paystation and that conductors 42 and 86 are connected as shown. When the paystation line originates a call by the 15 operation of his hand generator, the line relay 11 is energized. Relay 11 in addition to closing a locking circuit through its lower winding also completes a circuit over conductor 42 for energizing relay 43 (Fig. 4) in the paystation tone 20 relay group. At armature 47 relay 43 completes a locking circuit for itself from grounded armature 48 and at armature 46 prepares a point in the circuit for connecting paystation tone to the control trunk by way of conductors 85 and 270. 25 Start relay 201 also energizes in series with the line relay 11 to cause an idle finder to find the calling line and energize cut-off relay 12 as previously described. Cut-off relay 12 at armature 18 opens the locking circuit of relay 11 as well as 30 the original energizing circuit of relay 43. Relays 11 and 43 are now maintained energized from ground at armature 48. The same ground maintaining cut-off relay 12 energized now extends by way of conductor 86 to energize relay 82. At 35 armature 83 relay 82 completes a point in the circuit for connecting paystation tone to the control trunk conductor 270.

When the control operator answers the call, relays 302, 305 and 306 energize as previously 40 described. At armature 322 relay 305 completes the circuit for energizing relay 81 which starts its weighted spring vibrating. Relay 45 is a slow to operate relay and therefore does not fully 45 energize while spring 80 is vibrating. At armature 389 relay 306 completes a circuit through the lower winding of differential relay 84. Relay 84 energizes and at armature 49 completes a circuit through its upper winding to deenergize such 50 relay, whereupon armature 49 is opened. When armature 49 is opened differential relay 84 again energizes over its lower winding and again closes 55 armature 49 to cause the deenergization of such relay. Differential relay 84 therefore operates in the manner of a buzzer to generate a tone which 60 is now connected by way of condenser 50, armatures 83 and 46, and conductors 85 and 270 to the control trunk. A predetermined time after 65 relay 81 is energized the vibrating spring 80 is maintained in operated position with the result that slow-to-operate relay 45 energizes. Since 70 the weighted spring 80 continues to vibrate for a predetermined time the slow-to-operate relay 45 will not be operated until a certain period of time has elapsed. Relay 45, upon energizing, at armature 48 opens the locking circuit of relays 43 and 11. At armature 46 relay 43 disconnects the tone 75 from the control trunk and relay 11, upon deenergizing completes the talking circuit between the control operator and the paystation subscriber at armature 15. It will be appreciated that the paystation tone is generated each time the common equipment is taken into use by the control operator and if relay 82 were omitted there would be danger of the control operator 90 hearing paystation tone when answering a regu-

lar subscriber in case a paystation subscriber originated a call very shortly after such regular subscriber. For example, it will be assumed that a regular magneto subscriber has called and signalled the operator and before such operator answers this call a paystation subscriber originates another call. In this case relay 43 is energized but since the distributor is in use and has not been released to allow a finder to find the calling paystation line relay 82 is not energized 10 and therefore paystation tone is not connected to the trunk when the operator answers the call made by the regulator magneto subscriber. In this assumed case, if relay 82 was omitted then when the operator answered the regular magneto 15 subscriber's call she would hear paystation tone thereby giving her a false indication. By the inclusion of relay 82 the paystation tone is only connected to the trunk when a finder has connected with a paystation line and the common 20 equipment is taken into use for such a call.

Having described the invention, what is considered to be new and is desired to have protected by Letters Patent will be set forth in the following claims.

What is claimed is:

1. In a telephone system, a local exchange, local subscribers' lines terminating in said exchange, automatic switches in said exchange for completing connections between said local subscribers' lines, a pair of conductors extending from said local exchange to a remote operator, means responsive to a local subscriber calling for automatically signalling the remote operator over said conductors and for selecting one of said switches, means at the local exchange controlled by the operator over a circuit including both said conductors in series for operating said one switch into connection with the called line, and means at the local exchange controlled by the operator over a circuit including both said conductors in parallel for ringing the called subscriber by way of said switch. 30

2. In a telephone system, a local exchange, local subscribers' lines terminating in said exchange, automatic switches in said exchange for completing connections between said local subscribers' lines, a pair of conductors extending from said local exchange to a remote operator, means at the local exchange responsive to a local subscriber calling for temporarily opening said conductors and for selecting one of said switches, means at the remote operator's position operated in response to the opening of said conductors for signalling the remote operator, a line relay at the local exchange common to all said switches, operator controlled means for operating said line relay over a circuit including both said conductors in series, means for operating said one switch to extend a connection to a called line in response to said relay operations, and means at the local exchange controlled by the operator over a circuit including both said conductors in parallel for ringing the called subscriber. 45

3. In a telephone system, a local exchange, local subscribers' lines terminating in said exchange, automatic switches in said exchange for completing connections between said local subscribers' lines, a pair of conductors extending from said local exchange to a remote operator, means responsive to a local subscriber calling for automatically signalling the remote operator over said conductors and for selecting one of said switches, means at the local exchange controlled by the operator over a circuit including both said 50

- conductors in series for operating said one switch into connection with the called line, a differential relay in the local exchange connected to both said conductors, means controlled by the operator for operating said differential relay over a circuit including both said conductors in parallel, and ringing means at the local exchange for connecting ringing current to the called line by way of said operated switch in response to said relay 10 operations.
4. In a telephone system, a local exchange, local subscribers' lines terminating in said exchange, automatic switches in said exchange for completing connections between said local subscribers' lines, a pair of conductors extending from said local exchange to a remote operator, means responsive to a local subscriber calling for automatically signalling the remote operator over said conductors, for automatically selecting one of said switches, and for operatively connecting the calling line in a talking circuit over said conductors, means at the local exchange controlled by the operator dialling the digits of the called line over a circuit including both said conductors in series for operating said switch into connection with the called line, means at the local exchange automatically operated after the dialling period for automatically disconnecting the calling line from said conductors and for connecting the called line to said conductors to complete a talking circuit between the called line and the operator excluding the calling line, means at the local exchange controlled by the operator over a circuit including both said conductors in parallel, and means at the local exchange for reconnecting the calling line to said conductors in response to the first actuation of said last means and for connecting ringing current to the called line in response to subsequent 40 actuations of said last means.
5. In a telephone system, a local exchange, local subscribers' lines terminating in said exchange, automatic switches in said exchange for completing connections between said local subscribers' lines, a control trunk extending from said local exchange to a remote operator, means responsive to a local subscriber calling for automatically signalling the remote operator over said control trunk and for automatically connecting the calling line to said control trunk, means in the local exchange common to all said switches controlled by the operator dialling the digits of the called line over said control trunk for operating one of said switches into connection with the called line, and means in said local exchange common to all said switches automatically operated after the dialling period for automatically disconnecting the calling line from the control trunk and for connecting the called line to the control trunk.
6. In a telephone system, a local exchange, local subscribers' lines terminating in said exchange, automatic switches in said exchange for completing connections between said local subscribers' lines, a control trunk extending from said local exchange to a remote operator, means responsive to a local subscriber calling for automatically signalling the remote operator over said control trunk and for automatically connecting the calling line to said control trunk, means controlled by the operator dialling the digits of the called line over said control trunk for operating one of said switches into connection with the called line, means automatically op- 50 erated after the dialling period for automatically disconnecting the calling line from the control trunk and for connecting the called line to the control trunk, and means at the local exchange controlled by the remote operator for first reconnecting the calling line to the control trunk and for then connecting ringing current to the called line by way of said operated switch.
7. In a telephone system, a local exchange, local subscribers' lines terminating in said exchange, automatic switches in said exchange for completing connections between said local subscribers' lines, a control trunk extending from said local exchange to a remote operator, means responsive to a local subscriber calling for automatically signalling the remote operator over said control trunk and for automatically connecting the calling line to said control trunk, means controlled by the operator dialling the digits of the called line over said control trunk for operating one of said switches into connection with the called line, means automatically operated after the dialling period for automatically disconnecting the calling line from the control trunk and for connecting the called line to the control trunk, a relay at the local exchange, operator controlled means for controlling the operations of said relay over said control trunk, means responsive to the first operation of said relay for reconnecting the calling line to said control trunk, and means responsive to the second and subsequent operations of said relay for connecting ringing current to the called line.
8. In a telephone system, subscribers' lines, a plurality of links, operator controlled means for operating said links to complete connections between calling and called subscribers' lines, subscriber controlled means for releasing and restoring the links used in such connections, means for automatically signalling the operator in case all said links are in operated position, means for enabling the operator to supervise and restore the links which the subscribers failed to restore after conversation, and means operated in case the operator answers the signal and disconnects without supervising the links for automatically re-signalling the operator.
9. In a telephone system, subscribers' lines, means individual to a calling one of said lines for transmitting a splash of current in response to the calling subscriber removing his receiver, means responsive thereto for automatically signalling an operator, said individual means feeding talking battery to the calling line, operator controlled means for completing a connection to another subscriber's line, said individual means operated responsive to the calling subscriber replacing his receiver for transmitting a splash of current, and means operated responsive thereto for releasing said connection.
10. In a telephone system, subscribers' lines, operator controlled means for completing a connection between a calling line and a called line, means individual to the called line for feeding talking battery to the called line, said individual means operated responsive to the called subscriber replacing his receiver for transmitting a splash of current, and means operated responsive thereto for releasing said connection.
11. In a telephone system, a local exchange, common battery subscribers' lines terminating in said exchange, each common battery line having an individual line converting and battery feeding means, means for operating said individual means in response to a subscriber removing his receiver

- on the initiation of a call and in response to such subscriber replacing his receiver on the termination of a call, signalling means for signalling an operator operated in response to the operation of 5 said individual means on initiation of a call by a common battery subscriber, operator controlled means for establishing a connection between any two of said lines, and subscriber controlled releasing means operated responsive to the operation 10 of said individual means on the replacement of the receiver of a connected common battery line for releasing an established connection.
12. In a telephone system, a common battery called party line, a line circuit individual thereto, 15 substation ringers on said line connected to one of the line conductors of said line and ground, means for connecting ringing current to said individual line circuit, means individual to said line responsive to the connection of said ringing 20 current to said line circuit for connecting said ringing current to said one line conductor of the called line, battery feeding means individual to said line disconnected from said line in response to the operation of said individual ringing means 25 during the ringing period.
13. In a telephone system, a common battery called party line, a line circuit individual thereto, substation ringers on said line connected to one of the line conductors of said line and ground, 30 means for connecting ringing current to said individual line circuit, means individual to said line responsive to the connection of ringing current to said line circuit for connecting said ringing current to said one line conductor of the called line, battery feeding means individual to said line disconnected from said line in response to the 35 operation of said individual ringing means during the ringing period, means for operating said battery feeding means during a non-ringing period in response to the called subscriber answering, and means controlled by said battery feeding means for disabling said individual ringing means.
14. In a telephone system wherein an operator at a main exchange remote from a local exchange 45 controls automatic switches in the local exchange over a common control trunk to complete direct connections between local subscribers' lines, and circuit arrangements for completing a talking circuit including a repeating coil in the common control 50 trunk between the local calling and called subscribers' lines with the control trunk conductors bridged across one side of the repeating coil.
15. In a telephone system wherein an operator at a main exchange remote from a local exchange 55 controls automatic switches in the local exchange over a common control trunk to complete direct connections between local subscribers' lines, circuit arrangements for completing a talking circuit including a repeating coil in the common control 60 trunk between the local calling and called subscribers' lines with the control trunk conductors bridged across one side of the repeating coil, and operator controlled means for completing a direct 65 talking circuit between the local subscribers' lines excluding said repeating coil and said control trunk.
16. In a telephone system, a called party line having two line conductors, two groups of subscribers' substations connected to said conductors, the first group having their ringers connected to one line conductor of said line and ground, the second group having their ringers connected to the other line conductor of said 75 line and ground, a ringing relay, a ring reversing relay, selective means for preparing only the ringing relay for operation in case the called subscriber's ringer is connected to said one line conductor or for preparing said ring reversing relay for operation in case the called subscriber's ringer is connected to said other line conductor, means for operating the selected and prepared one of said relays in accordance with the code of the called subscriber, means controlled by said ring reversing relay for operating said ringing relay 10 each time said ring reversing relay is operated, and means operated by said ringing relay for connecting ringing current to said one line conductor in case said ringing relay is operated alone or for connecting ringing current to said other line conductor in case both said ringing relay and said ring reversing relay are operated to code ring the called subscriber. 15
17. In a telephone system wherein an operator remote from a local exchange controls automatic switches in the local exchange over a common control trunk to complete direct connections between local subscribers' lines in response to any local subscriber initiating a call, local paystation lines also terminating in the local exchange, paystation tone generating means in the local exchange, means responsive to a paystation line initiating a call for preparing the connection of said tone generating means to said control trunk, means for connecting the calling line 20 to said control trunk, and means responsive to said connection for completing the prepared connection of said tone generating means to said control trunk. 25
18. In a telephone system, links for connecting calling and called subscribers' lines, a supervisory switch, wipers on said switch having access to the talking conductors of said links, operator controlled means for operating said switch wipers into engagement with the talking conductors of said links regardless of their idle or busy condition to enable the operator to supervise and determine if the links are busy, and a rectifier bridged across said wipers to prevent disturbance on the line conductors of the links in use during supervision. 30
19. In a telephone system, links for connecting calling and called subscribers' lines, talking conductors in said links, a talking circuit including two line conductors, means for successively connecting said two line conductors of said talking circuit to the talking conductors of said links regardless of their busy or idle condition, and a rectifier bridged across the two line conductors of said talking circuit to prevent disturbances on the talking conductors of said links in use during successive connections. 35
20. In a telephone system wherein a control operator remote from a local exchange controls automatic switches in the local exchange over a common control trunk to complete direct connections between local subscribers' lines and toll lines terminating in the local exchange, means responsive to a toll operator initiating a call over one of said toll lines or responsive to a subscriber initiating a call for signalling the control operator over said control trunk and for selecting one of said switches, means controlled by the control operator on said control trunk for operating said switch into connection with the called subscriber's line, subscriber controlled means in said switch for releasing said switch in case two subscribers' lines are connected together, and means in said switch for disabling said subscriber controlled means and for transferring the control of 40

the release of said switch to the toll operator in case the calling toll line is connected to a called subscriber's line.

21. In a telephone system wherein a control operator remote from a local exchange controls automatic switches in the local exchange over a common control trunk to complete direction connections between local subscribers' lines and toll lines terminating in the local exchange, means in 10 the local exchange responsive to a toll operator initiating a call over one of said toll lines for signalling the control operator over said control trunk and for selecting one of said switches, means in the local exchange controlled by the 15 control operator over said control trunk for operating said selected switch into connection with a desired called subscriber's line, and means in the local exchange controlled by the toll operator for releasing said switch.

22. In a telephone system, a local exchange, local subscribers' lines terminating in said exchange, a pair of conductors extending from said exchange to a remote operator, means responsive to a local subscriber calling for automatically signalling the remote operator over said conductors, a differential relay at the local exchange connected to both said conductors, operator controlled means for operating said relay over a circuit including both said conductors in parallel, and ringing means at the local exchange controlled by actuations of said relay for transmitting ringing current back over said calling line to ring the called subscriber in case the called subscriber's substation is on the same line 15 as the calling substation. 5 10

EDWARD S. PETERSON.
